COMBINED LOCK PLATE AND HASP

Wallace E. Atkinson, Petersburg, Va., assignor to Long Manufacturing Company, Inc., Petersburg, Va., a corporation of Virginia

Application December 7, 1953, Serial No. 27,958

Term of patent 14 years

(Cl. D50—7)

Fig. 1.

Fig. 3.

Fig. 2.

Fig. 4.

Fig. 5.

Figure 1 is a front elevation of a combined lock plate and hasp embodying my new design;

Figure 2 is a top plan view of the same;

Figure 3 is a side elevation of the same, viewed from the left of Figure 1;

Figure 4 is a rear elevation of the same; and

Figure 5 is a perspective view of the same.

I claim:

The ornamental design for a combined lock plate and hasp, as shown.
